ABSTRACT

A cover, surrounding commonly coupled slider for paired resistors actuated by a common actuator, carries at least one hole permitting access to an adjusting mechanism for shifting one slider relative to the other and to overcome interlock error in a multi-stage interlock type variable resistor.

4 Claims, 12 Drawing Figures

FIG. 1**FIG. 2****FIG. 3****FIG. 4****FIG. 5****FIG. 6**

FIG. 7**FIG. 8****FIG. 9****FIG. 10****FIG. 11****FIG. 12**## MULTIPLE STAGE INTERLOCK TYPE VARIABLE RESISTOR

BACKGROUND OF THE INVENTION

1. FIELD OF THE INVENTION

The present invention relates to a multiple stage interlock type variable resistor and, more particularly, to a resistor of the rotary or slide type in which the interlock error resulting during assembling of the multiple stage resistor may be readily corrected.

2. DESCRIPTION OF THE PRIOR ART

Heretofore, the regulation of the interlocking error, which is produced when assembling two variable resistors into a common assembly for operation by a single actuator, has been generally corrected prior to assembly of a cover which occurs during the final process in the assembly of the multi-stage variable resistor, so that when an interlocking error is produced between two resistors after assembly, the correction thereof must be carried out by removing the cover at the occasion of each error. This operation is not only extremely troublesome, but also the parts of the variable resistor may be marred or damaged during the removal of the cover which injures the commercial value of the same.

The present invention allows ready correction for the interlocking error after assembly and without the necessity of removing the cover by a simple expedient without appreciably increasing the cost of the resistor.

BRIEF DESCRIPTION OF THE DRAWINGS

FIG. 1 is a perspective view of a multi-stage variable resistor constituting one embodiment of the present invention.

FIG. 2 is a sectional, side elevation of the resistor of FIG. 1.

FIG. 3 is a perspective view, partially broken away, showing the essential elements of the front and rear slider supports and the rotating shaft supporting the same.

FIG. 4 is an enlarged perspective view of portions of the variable resistor of FIG. 1 showing the technique of adjusting the resistor to overcome the interlocking error using a tool T.

FIG. 5 is a perspective view, partially broken away, of the resistor of FIG. 1 slightly modified from the illustration of FIG. 3.

FIG. 6 is an enlarged, perspective view of the essential parts of the resistor of FIG. 1 in modified form for adjusting the resistor which incorporates the elements of FIG. 5 therein.

FIG. 7 is a perspective view of a modified multi-stage variable resistor forming a third embodiment of the present invention.

FIG. 8 is a sectional, side elevational view of the resistor of FIG. 7.

FIG. 9 is a perspective view of a slide type variable resistor forming another embodiment of the present invention.

FIG. 10 is an end, sectional elevational view of the variable resistor of FIG. 9.

FIG. 11 is an enlarged perspective view of portions of the resistor of FIGS. 9 and 10.

FIG. 12 is an enlarged perspective view of portions of the resistor of FIG. 9 illustrating the manner of adjustment for interlocking error.

DESCRIPTION OF THE PREFERRED EMBODIMENTS

The explanation of the present invention is given with respect to a plurality of embodiments, all of which carry similar elements giving similar numerical designations. In this respect, a rotary type variable resistor is illustrated in FIGS. 1-6 which incorporates the invention in one form. A front stage variable resistor is indicated generally at 1, while a rear stage variable resistor is indicated generally at 2, both stages being operated commonly by a rotating shaft 3 which is mounted for rotation within a cover 9 by means of bearing 4. An insulating base plate 1_a for the front stage resistor 1 supports the bearing 4 and additionally a resistor 5 as well as a conducting plate 6 which are secured thereto in a well known manner.

The slider support 1_b, FIG. 3 receives projecting, elongated portion 3_a of the rotatable shaft 3, the slider support being formed of insulating material. The slider support carries slider 7 which slidably contacts the resistor 5 during rotation of shaft 3 and the conducting plate 6, the slider 7 being fixed to slider support 1_b. A metal plate 8 is superposed with and enforceably fitted to the front stage slider support 1_b, the metal plate serving as a stop for the rotating shaft as well as an electrical shield between the variable resistors 1 and 2 of the front and rear stages respectively. A cover 9 which is fixed to the front stage insulating plate 1_a by means of bent tabs 9₁ is further fixed to the insulating plate 2_a of the rear stage by means of the similar bent over tabs 9_a. A resistor 5 and a conductive plate 6 are fixed to the insulating base plate 2_a of the rear stage by conventional means in similar fashion to the front stage resistor.

A slider support 2_b of disc form in similar fashion to the slider support 1_b of the front stage, receives the inserted, elongated portion 3_a of rotating shaft 3 in a manner similar to that of the slider support 1_b, the slider support 2_b being also formed of an electrically insulating material. A slider 7 is likewise carried on the slider support 2_b and is in contact with resistor 5 in the conducting plate 6 of the rear stage resistor, slider 7 being fixed to slider support 2_b.

As seen from the drawing, and in particular in FIG. 3, the rear stage slider support 2_b is coupled to the rotating shaft by receiving the elongated portion 3_a of the rotating shaft 3, which is non-circular in cross-sectional configuration and being provided with two opposed flattened sides, the opening within the rear stage slider support 2_b conforming closely with the elongated portion 3_a of the rotating shaft such that there is no relative rotation between the rear stage slider support 2_b and shaft 3. Further, the rear stage slider support 2_b is carried on the rotating shaft 3 as is metal plate 1_b and the front stage slider support 1_b in such a manner that the three members 2_b, 1_b, and 8 are pressed against one another. In this regard, the metal plate 8 and one of the front and rear slider supports (in this case, rear slider support 2_b), is forcefully fitted onto the elongated shaft portion 3_a such that relative rotation occurs between these parts. In contrast, the other slider support (in this case, front stage slider support 1_b) is provided with a somewhat larger hole 1_b than the elongated portion 3_a of the shaft, so that when the slider support 1_b is rotated in opposition to the force pressing supports 1_b, 2_b, and plate 8 together, it may be rotated slightly on the rotat-

ing shaft 3 relative to plate 8 and the relatively fixed rear slider support 2_b. Further, in this regard, a hole 9_b (see FIG. 1) is provided within the cover 9 at a position and in longitudinal alignment with slider support 1_b, such that the interlocking error may be regulated and eliminated by rotating slider support 1_b slightly on the shaft 3 by the act of causing the tip end of tool T to engage the rotatable slider support 1_b and by moving tool T in either of two directions as indicated by the double headed arrow in FIG. 4. In order to facilitate the engagement of the tool T and the slider support 1_b, the rotatable slider support 1_b is formed with peripheral recesses or teeth. Alternatively, as illustrated in FIG. 6 with a two tip tool, as illustrated in FIG. 5, both peripheries of the slider supports 1_b and 2_b are provided with recesses or cut portions as at 1_b₁ and 2_b₂, with a two prong tool T, FIG. 6, permitting rotation in either direction.

In operation, when the rotating shaft 3 of the variable resistor assembly is rotated, the front and rear stage slider supports 1_b, 2_b and the metal plate 8 are rotated in unison which also rotates the sliders 7 fixed to the slider supports 1_b and 2_b. The sliders 7 slide on and in contact with the resistor 5 and conducting plate 6, whereby the resistance values of the front and rear stage variable resistors 1 and 2 are readily varied.

When the resistance values of the front and rear stage variable resistors 1 and 2 do not coincide, due to the error of the parts, or due to error during assembly, thus resulting in an interlocking error subsequent to assembly, the relative position between the slider supports 1_b and 2_b may be shifted by inserting the tool T into the hole 9_b of the cover 9, causing the tip portion of the tool to engage with at least one of the rotatable slider supports such as rotatable slider support 1_b, FIG. 4, and by moving the tool T, a regulation of the interlocking error may be effected externally of the cover without the necessity of disassembling the variable resistor.

Now, a modified embodiment of the rotary type variable resistor as illustrated in FIGS. 7 and 8 will be explained, in which in the drawings and in the description the same reference numerals are employed for the same elements as in the previous embodiment. This embodiment has the same construction as that previously described, except that the front and rear variable resistors 1 and 2 are formed by separate covers 9₁ and 9₂ and further the front and rear slider supports 1_b and 2_b and the sliders 7 are accommodated in separate covers 9₁ and 9₂ respectively, so that the detailed explanation is necessarily omitted. In all other ways, the embodiment is similar to that previously described except in this case, it is the slider support 2_b that is made rotatable slightly on the rotating shaft 3 and triangular teeth are formed on the periphery of the slider support 2_b so that the tool T may be engaged therewith easily, and in this case, the regulating hole 9_b is provided in cover 9₂.

The present invention is next explained as it is applied to a slide type variable resistor illustrated in FIGS. 9-12 and again, the same reference numerals are employed to illustrate the parts corresponding to those appearing in the rotary type variable resistors previously described. The numeral 1 designates one of the variable resistors, while the other variable resistor is indicated at 2. A box type cover 9 is provided with a rectangular opening 9' and an insulating base plate 10 is fixed to the lower portion of the cover 9. Resistors 5 are

fixed in parallel on the insulating base plate 10 as are conducting plates 6 and provided at positions corresponding to each of the resistors 5. A metal plate 8 is fixed to the cover, FIG. 9, which serves as a shield between both variable resistors 1 and 2. A slider 11 is accommodated in the cover 10 and is formed of an insulating material, the slider 11 consisting of a main body 11_a, a knob 11_a₁ protruding integrally from the main body 11_a and through the openings 9' within the upper surface of cover 9. Sliders 7 are fixed on the lower surfaces of the main body 11_a and the movable portion 11_b of the body and are slidably in contact with the resistors and the conducting plates. Thus, by shifting of knob 11_a₁, sliders 7 slide on the resistors 5 and the conducting plate 6, whereby the resistance values of both variable resistors 1 and 2 are changed, FIG. 10. A regulating hole 9_b is provided in the cover 9 on the side closest to the movable portion 11_b of the slider assembly 11 and the movable portion 11_b may be moved relative to the main portion or main body 11_a by engaging the tip portion of a tool T within an engaging hole 11_b₂ of a movable portion 11_b, which preliminarily passes through a hole 11_a₂ of the main body 11_a and moving the tool in one of two directions as shown by the arrows in FIG. 12. Thus, the relative position of the main body 11_a and the movable portion 11_b of the slider assembly 11, may be shifted. Thus, again it is possible to regulate the resistor to adjust for the interlocking error without removing the cover.

By forming the slider assembly with an elastic synthetic resin, and by wedge fitting the main body 11_a and the movable portion 11_b, both portions can be coupled firmly without any coupling members required.

Being thus constituted, it is possible, according to the present invention, to carry out simply and easily the regulation and adjustment of interlocking error without the need of disassembling a multi-stage variable resistor, so that the productivity thereof is highly improved.

What is claimed is:

1. In a multi-stage resistor comprising a cover surrounding first and second fixed resistors, first and second sliders mounted within said cover for sliding contact respectively with said first and second resistors, a common actuator for moving said sliders in unison, and means permitting adjustment in position of one slider relative to the other to correct for interlocking error existing between said resistors, the improvement comprising:

an opening within said cover overlying one of said sliders, and
adjustment means carried by said one slider and in alignment with said opening,
whereby, insertion of a tool within said opening and in contact with said means, permits adjustment in the position of one slider with respect to the other.

2. The multi-stage resistor as claimed in claim 1, wherein said first and second fixed resistors are annular in form, a rotatable shaft extends coaxially through said resistors, said sliders are fixed respectively to slider supports carried by said rotatable shaft adjacent respective resistors, said means permitting adjustment comprises means fixing one of said slider supports to said rotatable shaft and means for mounting the other of said slider supports on said shaft for slight rotation therewith, and means normally biasing said slider supports in frictional contact with each other but permitting, in response to tool insertion, slight relative rotation about

the shaft axis between said slider supports to correct for interlocking error.

3. The multi-stage resistor as claimed in claim 1, wherein said resistors comprise spaced parallel elongated members, said first and second sliders comprise an elongated main body and a relatively movable body operatively associated with respective resistors within said cover and defining an assembly, said movable body faces said hole within said cover, said movable body includes an opening in line with said cover hole and in line with a recess within said main body, whereby; in-

sertion of a tool through said cover opening, said movable body opening and said recess within said main body, permits longitudinal shifting of said movable body relative to said main body to correct for said interlocking error.

4. The multi-stage resistor as claimed in claim 3, wherein said main body and said movable body comprise elastic synthetic resin, and wherein said means for coupling said sliders together comprise an interfitting wedge lock between said bodies.
